DESIGN FOR A MUFF

Max Baer, New York, N. Y.

Application May 23, 1941, Serial No. 101,103

Term of patent 3½ years

To all whom it may concern:

Be it known that I, Max Baer, a citizen of the United States, residing in New York city, in the county of Bronx and State of New York, have invented a new, original, and ornamental Design for a Muff, of which the following is a specification, reference being had to the accompanying drawing, forming part thereof.

Fig. 1 is a side perspective view of a muff showing my new design.

Fig. 2 is one end elevational view thereof; and Fig. 3 is the other end elevational view thereof with the handle omitted.

I claim:

The ornamental design for a muff, substantially as shown.

MAX BAER.
